[57] **CLAIM**

The ornamental design for a combined holder for an ink pen and tally card, as shown and described.

DESCRIPTION

FIG. 1 is a perspective view of a combined holder for an ink pen and tally card showing my new design;

FIG. 2 is a second perspective view thereof, the ink pen and tally card depicted by means of broken lines being shown for illustrative purposes only and forming no part of the claimed design;

FIG. 3 is a top plan view of FIG. 1;

FIG. 4 is a front elevational view of FIG. 1;

FIG. 5 is a bottom plan view of FIG. 1;

FIG. 6 is a right side elevational view of FIG. 1;

FIG. 7 is a left side elevational view of FIG. 1; and,

FIG. 8 is a rear elevational view of FIG. 1.

The inset circle and indicia depicted by means of broken lines in FIGS. 1 through 4 has been shown for illustrative purposes only and forms no part of the claimed design.
